ABSTRACT

A process for making uranium metal from uranium oxide by first fluorinating uranium oxide to form uranium tetrafluoride and next electrolytically reducing the uranium tetrafluoride with a carbon anode to form uranium metal and CF₄. The CF₄ is reused in the fluorination reaction rather than being disposed of as a hazardous waste.

2 Claims, 1 Drawing Sheet

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

PROCESS FOR ELECTROLYTICALLY PREPARING URANIUM METAL

The invention was developed pursuant to a contract with the U.S. Department of Energy.

This invention relates to a process for making uranium metal from uranium oxide using a fluorination by CF_4 and then by electrolytically converting UF_4 to U. Since CF_4 is the fluorinating agent for making the UF_4 as well as the by-product of the electrolysis it is regenerated and reused in the process.

BACKGROUND OF THE INVENTION

Electrolytic reduction has been studied for the preparation of uranium metal from uranium oxides. The desired overall reaction is $\text{UO}_2 + 2\text{C} \rightarrow 2\text{CO} + \text{U}$, and the process has many similarities to the Hall-Heroult processes for preparation of aluminum from aluminum oxide using molten cryolite. At temperatures above the melting point of uranium, uranium metal product of good purity was achieved but yields and current efficiencies were very low. Satisfactory feed of UO_2 to electrolytic cells is much more difficult than the feed of Al_2O_3 to Hall cells. The solubility of UO_2 is about one-tenth that of Al_2O_3 in Hall cells and the dense UO_2 settles to the bottom where it fouls the metal surface.

Yields and current efficiencies were improved by using compartmental cells to confine the oxide feed and prevent fouling of the metal surfaces. The current efficiencies were 31% as a maximum, and the cell design was not suited to scale-up to large size.

An alternative reduction reaction, $\text{UF}_4 + \text{C} \rightarrow \text{CF}_4 + \text{U}$, is possible. However, this reaction requires a makeup of UF_4 which is made from the reaction of UO_2 and large amounts of HF, a very costly chemical. Furthermore, CF_4 is a more troublesome gaseous waste than is CO.

Preparation of uranium in electrolytic cells has been successfully demonstrated. One study showed good cell operation using UF_6 as the feed. In another case, a large electrolytic cell was operated with 30 to 50% of the U metal from reduction of UO_2 , 50 to 70% from reduction of UF_4 . The objective of these studies was to maximize the amount of UO_2 feed; the higher the percentages of UF_4 were easier to use, but a large fraction of UF_4 feed with little UO_2 was not tested. A problem revealed by these studies was that UO_2 settled out in the electrolysis cell due to its low solubility and high density.

SUMMARY OF THE INVENTION

In view of the above needs, it is an object of this invention to provide a process for electrolytically preparing uranium metal from UF_4 with a recycling of the fluoride.

It is another object of this invention to provide a process for electrolytically preparing uranium metal wherein fouling of the electrolytic cell is minimized.

Additional objects, advantages and novel features of the invention will be set forth in part in the description which follows, and in part will become apparent to those skilled in the art upon examination of the following or may be learned by practice of the invention. The objects and advantages of the invention may be realized and attained by means of the instrumentalities and combinations particularly pointed out in the appended claims.

To achieve the foregoing and other objects and in accordance with the purpose of the present invention, as embodied and broadly described herein, the process of this invention may comprise: a first reaction wherein a fluoride and UO_2 are reacted to form UF_4 ; a second reaction wherein the UF_4 formed in the first reaction is electrolytically converted to U⁺ by using a carbon anode resulting in the formation of CF_4 as by-product, and subsequent to the second reaction, the CF_4 formed is recycled into the first reaction for reuse as fluorinating agent. The process allows the recycling of a troublesome fluorocarbon, CF_4 , and also minimizes the feed of UO_2 to the electrolytic cell thus avoiding the problem of fouling the metal surface. Also the consumption of the carbon anode is reduced since the waste product is CO_2 instead of CO.

FIGURE

The FIGURE is a schematic chemical flowsheet representing the electrolytic reduction process of this invention.

DETAILED DESCRIPTION OF THE PREFERRED EMBODIMENT

The invention is a combination of an electrolytic cell where the principal overall reaction is $\text{UF}_4 + \text{C} \rightarrow \text{CF}_4 + \text{U}^+$ with a feed reactor where the primary reaction is

$\text{CF}_4 + \text{UO}_2 \rightarrow \text{UF}_4 + \text{CO}_2$. The two reactions together give the preferred overall reaction $\text{UO}_2 + \text{C} \rightarrow \text{CO}_2 + \text{U}^+$. Moderate amounts of UO_2 that remain in the UF_4 feed to the cell will dissolve and produce metal by the overall reaction $\text{UO}_2 + 2\text{C} \rightarrow 2\text{CO} + \text{U}^+$. The utilization of two separate reactors allows separate optimization of the operating conditions of each reaction. The electrolytic cell is optimized for reduction to metal without concern about the amounts of CO and CF_4 products. The feed reactor is optimized for recycle of fluorides as UF_4 to give an efficient conversion of reactants to UF_4 , thus eliminating the mixing and settling of UO_2 solids as a cell operating problem. The consumption of anode carbon is reduced because the final by-product is mostly CO_2 instead of CO.

The reactions of CF_4 with uranium oxides are thermodynamically favorable. A number of reactions can be written with UO_2 and CF_4 as reactants and UF_4 as one product. Some of interest are:

Both these reactions are favored with $\Sigma \nabla_f G^\circ$ of -310 KJ mol⁻¹ and equilibrium constants at 1100° K. of about 5×10^{14} . This result agrees with the behavior in-cell where UF_4 reacts to form CF_4 only when there is a deficiency of UO_2 . The second reaction is probably more favorable as an excess of H_2 and the two gaseous products should allow a more complete utilization of the CF_4 . The H_2 can also provide a complete reduction of U(VI) to U(IV).

The modified electrolytic reduction process can be shown as a schematic chemical flowsheet as shown in the FIGURE. Fluorination 1 takes place in the fluorination and reduction reactor where UF_4 is produced to be sent to the electrolytic cell accompanied by a small amount of UO_2 . Also produced in the fluorination and reduction reactor are byproducts CO_2 , H_2O , H_2 , CO, HF and a small amount of CF_4 that are expelled as

offgases 5. The electrolytic reaction 3 takes place in the cell containing a carbon anode and produces uranium metal product as well as CF₄ by-product that is recycled to the fluorination reaction 1 along with a small amount of CO.

In prior studies of electrolytic reduction, the use of UO₂ was considered preferable to the use of UF₄ to avoid evolution of the undesirable CF₄ by-product. Therefore, even when UO₂ and UF₄ were used together as starting materials, which improved efficiency, the use of UF₄ was minimized to minimize CF₄ offgas. This invention solves that problem by reusing instead of disposing of waste CF₄.

I claim:

1. A process for converting UO₂ to uranium metal 15 ber. comprising:

a first reaction wherein a fluoride compound and UO₂ are reacted in a first reaction chamber to form UF₄;

5 a second reaction wherein said UF₄ and unreacted UO₂ are electrolytically converted in a second reaction chamber, said second reaction chamber being an electrolytic cell, to U° by using a carbon anode resulting in the formation of CF₄ as by-product; and subsequent to said second reaction, recycling said CF₄ into said first reaction for reuse of said fluoride.

2. The process of claim 1 wherein said first reaction further comprises adding H₂ in said first reaction chamber.
